(57) **CLAIM**

The ornamental design for a buckle assembly, as shown.

DESCRIPTION

FIG. 1 is a perspective view of portions of a buckle assembly showing my new design, the buckle assembly including a tongue and a buckle, and showing only the lock pawls of the buckle and the tongue, with the tongue being disengaged from the lock pawls;

FIG. 2 is a top plan view of the buckle assembly portions of FIG. 1, the bottom plan view being identical;

FIG. 3 is a left side elevational view of the buckle assembly portions of FIG. 1;

FIG. 4 is a right side elevational view of the buckle assembly portions of FIG. 1;

FIG. 5 is a front elevational view of the buckle assembly portions of FIG. 1;

FIG. 6 is a back elevational view of the buckle assembly portions of FIG. 1;

FIG. 7 is a perspective view similar to FIG. 1 but showing the remaining portions of the buckle, with the tongue being disengaged from the buckle;

FIG. 8 is a perspective view similar to FIG. 1 but showing the tongue in engagement with the lock pawls of the buckle;

FIG. 9 is a top plan view of the buckle assembly portions of FIG. 9, the bottom plan view being identical;

FIG. 10 is a left side elevational view of the buckle assembly portions of FIG. 9;

FIG. 11 is a right side elevational view of the buckle assembly portions of FIG. 9;

FIG. 12 is a front elevational view of the buckle assembly portions of FIG. 9;

FIG. 13 is a back elevational view of the buckle assembly portions of FIG. 9; and,

FIG. 14 is a perspective view showing the tongue and all the portions of the buckle, with the tongue being in engagement with the lock pawls of the buckle.

1 Claim, 10 Drawing Sheets

UNITED STATES PATENT AND TRADEMARK OFFICE
CERTIFICATE OF CORRECTION

PATENT NO. : D735,606 S
APPLICATION NO. : 29/490388
DATED : August 4, 2015
INVENTOR(S) : Neil Grant, Samir Chokshi and Troy Sauvé

Page 1 of 1

It is certified that error appears in the above-identified patent and that said Letters Patent is hereby corrected as shown below:

Title Page, item (72), in the Inventors section, inventor Neil Grant is listed as residing in Crysler, CA (United States). That is a typographical error. His correct residence is Crysler, Ontario, Canada.

Signed and Sealed this
Twenty-ninth Day of December, 2015

Michelle K. Lee
Director of the United States Patent and Trademark Office
